IMPROVEMENT IN FASTENINGS FOR BUTTONS.

JOHN M. JOHNSON, OF NEW YORK, N. Y.

Letters Patent No. 60,194, dated December 4, 1866.

SPECIFICATION.

Be it known that I, JOHN M. JOHNSON, of the city, county, and State of New York, have made a new and useful Improvement in Button Fastenings; and I do hereby declare the following to be a full, clear, and exact description of the same, which will enable others skilled in the art to make and use the same, reference being had to the accompanying drawings, forming part of this specification, in which—

Figure 1 represents a longitudinal central section of this invention, the line *v v*, fig. 3, indicating the plane of section.

Figure 2 is a detached elevation of the pointed stud which I use to pierce the cloth and fasten the button.

Figure 3 is a horizontal section of the same, taken in the plane indicated by the line *w w*, fig. 1.

Figure 4 is a horizontal section of a modification of the same.

Figures 5 and 6 are other horizontal sections of modifications of the same.

Figure 7 is a longitudinal central section of a modification of the same.

Similar letters of reference indicate like parts.

My invention consists in the arrangement of a spear or T-shaped shank, one or both ends of whose transverse part are provided with a spur at right angles thereto, in combination with a button whose collet is provided with a slot to admit the head of the shank, said collet having upon its inner sides and at an angle to the slot a depression on the one side and a hole through the collet on the other, or a hole on both sides, so that when the shank is introduced through the collet and the button partially rotated or slid, as in figs. 4 and 6, the hook or hooks will readily engage in the holes, and thus securely fasten the two parts together. A spring of India rubber, or other suitable material, may be interposed between the cloth and button, to more securely hold the parts in position, though the fabric will usually serve the same purpose. To detach the button it is only necessary to press the button against the stud and slightly turn it or slide it out.

A represents a pointed stud made of metal, or other suitable material, and provided with a shoulder, *a*, on one side, and a hook, *b*, on the other, as clearly shown in drawing, fig. 2; said stud is pointed sharp, so that by its aid the material to which a button is to be fastened can be readily pierced at the desired spot. A modification of the same is shown at *A*, fig. 7. The button, *C*, which is to be fastened by means of the pointed or unpointed stud, *A*, is provided with a slight socket or shoulder, *d*, the lower end of which is closed and provided with a slot corresponding with the width of the stud which enters therein. The inner face of this lower end is depressed on one side, with a hole and depression on the other, as shown at *e*, fig. 1, or it may have a hole and depression on either side, as shown at *ff*; fig. 3, so that when the button is turned after the entrance of the stud the shoulder and hook of the latter rest in the depressions and holes of the button, or the button may have a T-shaped opening with a groove and hole in one side, as shown at *g*, fig. 6, or it may have a hole and depression in either side, as shown at *h h*, fig. 4. When the socket or shoulder of the button is formed after this manner, the button is introduced on the stud through the opening *i i*, figs. 4 and 6, when it is pressed against the stud and slid up to the hole and depression *h h*, fig. 4, where it is held securely. In order to release the button it is only necessary to press it against the stud and turn it slightly, as shown in figs. 3 and 5, or move it out whilst pressing, as shown in figs. 4 and 6. By this arrangement a button can be readily fastened to a garment or other article without the aid of any other instrument, and can be readily detached therefrom. The stud, when properly introduced into the button, is not liable to become detached spontaneously. The fastening can be made very cheap, it is durable, and its operation is so simple that it can be readily understood by the simplest mind.

Having thus described my invention, what I claim as new, and desire to secure by Letters Patent, is—

A button whose collet is provided with a slot to admit the head of the shank, said collet having upon its inner side, and at an angle to the slot, a depression on one side and a hole on the other, or a hole upon each, in combination with a spear or T-shaped shank or stud, whose transverse end or ends are provided with a spur at right angles thereto, with or without the spring *J*, substantially in the manner and for the purpose described.

JOHN M. JOHNSON.
